UNITED STATES PATENT OFFICE.

HENRY CONRAD HEBIG, OF HEMPSTEAD, NEW YORK, ASSIGNOR TO WILLIAM P. HAMMOND, OF MAPLEWOOD, NEW JERSEY.

DESIGN FOR A KIDDIE-CAR.

58,750.

Specification for Design.

Patented Aug. 30, 1921.

Application filed May 26, 1921. Serial No. 472,906. Term of patent 14 years.

To all whom it may concern:

Be it known that I, HENRY CONRAD HEBIG, a citizen of the United States, residing in Hempstead, county of Nassau, and State of New York, have invented a new, original, and ornamental Design for a Kiddie-Car, of which the following is a specification, reference being had to the accompanying drawing, forming a part thereof.

Figure 1 is a view in side elevation of the kiddie car, embodying a design of my invention.

Fig. 2 is a front end view thereof, and
Fig. 3 is a top plan view thereof.

What I claim is—

The ornamental design for a kiddie car, as shown.

HENRY CONRAD HEBIG.
